UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

COVER PLATE FOR SEWING MACHINES

Application filed August 31, 1929. Serial No. 339,803.

This invention relates to new and useful improvements in cover plates for sewing machines, and particularly for use in connection with the forwardly extending arm of a blind 5 stitch sewing machine such as is disclosed in my Patent 1,739,081, Dec. 10, 1929.

In machines of the above type, the looper mechanism and the top feed mechanism extend along the lower part of the forwardly 10 extending arm and inasmuch as it is desirable to have access to these parts, it is necessary that a removable cover plate be provided and inasmuch as this cover plate must be supported from the arm, it is desirable to 15 provide means which will not only maintain the arm in operative position but which will also permit of the cover plate being readily removed or replaced whenever desired.

It is therefore the main object of my present 20 invention to provide a cover plate for a forwardly extending arm of a sewing machine, and connections between the arm and the cover plate which will permit the latter to be removed or replaced whenever desired 25 and which, when the cover plate is in operative position, will securely retain the latter against accidental displacement.

With these and other objects in view which will more fully appear, the nature of 30 the invention will be more clearly understood by following the description, the appended claims, and the several views illustrated in the accompanying drawings.

In the accompanying drawings:

35 Figure 1 shows a sewing machine equipped with a cover plate embodying my invention,

Figure 2 is a cross-sectional view taken on the line 2—2 of Figure 1, and

40 Figure 3 is a perspective view of the cover plate.

Like reference numerals designate corresponding parts throughout the several figures of the drawings.

45 Referring to the accompanying drawings, the sewing machine to which my invention is applied includes a base 5, a work arm 6, a standard 7 from the upper end of which projects an arm 8, and a needle arm 9 which extends forwardly from the arm 8 and terminates directly above the free end of the

work arm 6. In the needle arm 9 is a needle operating shaft 10 and the mechanisms for operating the top feed 11 and the looper 12, the shaft 10 only being disclosed.

The arm 9 which is of shell like formation 55 normally exposes the mechanisms therein, and includes a top wall 13 and spaced side walls 14 and 15 which are relatively short and tall.

The relatively short wall 14 is provided 60 with a lower horizontal edge 14^a, and the relatively long wall 15 is provided with a lower horizontal edge 15^a.

In order to cover the mechanisms within 65 the arm 9, I have provided a cover plate A which is formed from a single casting and includes a bottom 17, a relatively tall side wall 18 having an upper horizontal edge 18^a, a rear end wall 19, and a relatively short side wall 20 having an upper horizontal edge 20^a. 70 The upper edges of the walls 18 and 20 are adapted to abut the lower edges of the side walls 14 and 15, as shown particularly in Figure 2. The arm 9 is provided with spaced 75 and integral lugs or stops 16—16 which are located between the walls 14 and 15 adjacent the wall 14 and project downwardly therebelow. The side wall 18 is provided with a recess 21 which extends downwardly from the upper edge thereof and is located between the 80 stops 16—16 when the cover plate is in operative position. The wall 15 of the arm 9 is provided with a threaded opening 22 which is located opposite the recess 21, and threaded 85 into this opening 22 is a tubular housing 23. This housing is disposed within the arm 9 and extends transversely thereof, the inner end 24 of the housing being provided with an opening 25. A clamping bolt 26 has a reduced end 27 which slides in the opening 25. The free end of the reduced end 27 extends 90 beyond the wall 15 and has a sleeve 28 secured thereto by a pin 29, the outer end of the sleeve being provided with a head 30. The inner end of the sleeve 28 is spaced a considerable distance from the inner end 24 of the housing 23, and a coil spring 31 is disposed around the reduced end 27 and bears against the inner end 24 of the housing 23 and against 95 the inner end of the sleeve 28 so as to nor-

mally urge the clamping bolt toward the right as viewed in Figure 2. Thus the opening 25 and the sleeve 28 cooperate with the bolt and housing to form bearings for said bolt. Rigidly connected to the end of the bolt 26 opposite the reduced portion 27 thereof is a stop or head 32 which engages the outer face of the wall 18 and thereby frictionally retains the cover plate against accidental displacement, the bolt functioning to clamp the wall 18 between the stops 16-16 and the bolt head 32.

When it is desired to remove the cover plate, pressure on the head 30 will shift the locking bolt 26 longitudinally toward the left and thereby release the head 32 from said cover plate so as to permit the latter to be readily removed. When it is desired to replace the cover plate, the locking bolt 26 is again pushed toward the left as viewed in Figure 2, the cover plate is positioned with the recess 21 in registration with the bolt 26, and the locking bolt is then released.

It is of course to be understood that the details of structure and arrangements of parts may be variously changed and modified without departing from the spirit and scope of my invention.

I claim:

30 1. The combination of a sewing machine including a needle-arm having normally exposed operating mechanism therein, said arm including a top and side walls, a cover plate for said operating mechanism disposed below and abutting the lower edges of said side walls, a transversely disposed clamping bolt mounted on one of said walls for engagement with said cover plate, and a spring for normally holding said bolt in frictional contact with said cover plate.

40 2. The combination of a sewing machine including a needle-arm having normally exposed operating mechanism therein, said arm including a top and side walls, a cover plate for said operating mechanism disposed below and abutting the lower edges of said side walls, said plate including a bottom and an upwardly extending wall having a downwardly extending recess, a transversely disposed clamping bolt mounted on one of said walls and extending through said recess of the cover plate, and a spring for normally holding said bolt in frictional contact with said cover plate.

50 3. The combination of a sewing machine including a needle-arm having normally exposed operating mechanism therein, said arm including a top and relatively short and tall side walls, the short side wall being provided with spaced and downwardly extending stops, a cover plate for said operating mechanism disposed below and abutting the lower edges of said side walls, said plate including a bottom and an upwardly extending wall having a downwardly extending recess ar-

ranged intermediate said stops, a transversely disposed clamping bolt mounted on the tall side wall and extending through said recess of the cover plate and provided with a head cooperating with said stops, and a spring for normally holding said bolt head in frictional contact with said stops.

4. The combination of a sewing machine including a needle-arm having normally exposed operating mechanism therein, said arm including a top and relatively short and tall side walls, the short side wall being provided with spaced and downwardly extending stops, the tall side wall being provided with an opening opposite said stops, a cover plate for said operating mechanism disposed below and abutting the lower edges of said side walls, said plate including a bottom and an upwardly extending wall having a downwardly extending recess arranged intermediate said stops, a tubular housing extending transversely of the arm and having its outer ends secured in the opening of the tall wall, a clamping bolt mounted in said housing and extending through the recess in said cover plate and provided with a clamping head engageable with the plate on opposite sides of the recess, and a spring within the housing for urging the bolt in a direction to clamp the cover plate between the bolt head and the spaced stops.

In testimony whereof I hereunto affix my signature.
